DENTAL MATRIX RETAINER

Chester S. Ivory, Bala-Cynwyd, Pa., assignor to
the estate of J. W. Ivory, Philadelphia, Pa.

Application October 23, 1934, Serial No. 749,517

2 Claims. (Cl. 32—63)

My invention relates to a new and useful dental matrix retainer adapted for holding the matrix around a tooth during the filling of a cavity in such tooth, and it relates more particularly to a dental matrix retainer of a simplified construction to facilitate the engagement and disengagement of the retainer from the band or matrix while such matrix is in the mouth of a patient.

The present invention is an improvement over the construction disclosed in prior Patent No. 911,307, which consisted of a bracket having aligning slots at one end thereof, through which the free ends of the matrix were to be threaded, such slots being closed on all sides, thus necessitating exact and accurate insertion of the ends of the band in said slots and further necessitating the complete return of the matrix clamping member to its original position before the retainer could be disengaged from the matrix.

It is, therefore, the object of my invention to obviate the practical disadvantages inherent in the prior patent referred to by producing a novel matrix retainer construction which permits immediate engagement or disengagement of the retainer with respect to the matrix, without the exercise of any skill and without any inconvenience to the patient.

A further object of my invention is to produce a construction of this character which is equally applicable to teeth in the lower or the upper jaw and which can be used on inner and outer sides of the teeth with equal ease.

Other objects and advantages of the construction will be more clearly set forth in the specification taken in conjunction with the accompanying drawing, in which:

Fig. 1 represents a side elevation of my improved matrix retainer.

Fig. 2 represents a longitudinal section on line 2—2 of Fig. 3.

Fig. 3 represents a plan view of Fig. 1 showing the matrix retainer applied to a tooth, but before it is tightened.

Fig. 4 represents a bottom plan view of Fig. 3 showing the matrix retainer in position after it is tightened.

Fig. 5 represents a section on line 5—5 of Fig. 3.

Fig. 6 represents a bottom plan view of a modified construction.

Referring to the drawing in which like reference characters indicate like parts, my novel matrix retainer comprises a base bar or supporting member 1 which has at one end thereof the integral or fixed members 2 which are pro-

vided with aligning or registering slots 3. The slots 3 are open on all sides except at their terminals in the extension 4 of the base bar 1, as will be seen from Figs. 1, 3 and 4. In the base bar 1 is provided the slot 6, in which is slidably mounted the bracket 7 which is retained in position in said slot by the pin or key 8. The other end of the bar 1 is deflected upon itself to form the U-shaped member 9 consisting of the limbs 10 and 11. The outer limb 11 is slotted, as shown in Figs. 2 and 3, in order to engage the groove 12 of the threaded nut 13 which is provided with the knurled operating member 14. The nut 13 is therefore confined against longitudinal motion between the limbs 10 and 11 of the U-shaped member 9, as clearly shown in Figs. 1, 2 and 3. Passing through the nut 13 and the limbs 10 and 11 of the U-shaped member 9 is the shaft 16 which has the threaded portions 17 and 18 and which is provided with the outer operating handle 19 projecting beyond the nut 13. The threaded portion 17 of the shaft 16 actively engages a threaded aperture in the wall 20 of the bracket 7 but the threaded portion 18 of the shaft rotates freely and without engagement through the registering apertures in the U-shaped member 9. The threaded portion 18 of the shaft 16 is actively engaged by the nut 13. With this construction, if the operating end 19 of the shaft 16 is turned the front end 21 of the shaft 16 will be moved towards or away from the outer member 22 of the bracket 7, while the turning of the nut 13 on the threaded portion 18 of the shaft 16 results in the movement of the slide bracket 7 towards or away from the slotted members 2. The turning of the nut 13 does not in any way affect the position of the end 21 of the shaft 16 with respect to the outer member 22 of the slide bracket 7.

The operation is as follows: When it is desired to apply the matrix retainer, the nut 13 is turned in a counter-clockwise direction to bring the outer member 22 of the slide bracket 7 into alignment or registration with the extreme outer end of the slotted members 2, so that the outer edges or ends of the slotted members 2 and the outer member 22 of the slide bracket 7 are in line and the passage is clear between the slots 3. In this position of the parts the outer end 21 of the shaft 16 is about where it is shown in Fig. 2. The matrix band 24 is then disposed about the tooth 25, the cavity 26 of which is to be treated, and the gathered free ends 27 of the matrix band 24 are inserted into and through the aligning juxtaposed slots 3. The operating handle 19 of the

- shaft 16 is then turned to cause the end 21 of the shaft 16 tightly to clamp the free ends 27 of the matrix band 24 against the outer member 22 of the slide bracket 7, as clearly shown in Fig. 4. 5
5 In order to tighten the matrix band around the tooth, the slide operating nut 13 is turned in clockwise direction, thus pulling the clamped ends 27 of the matrix band 24 away from and out of alignment with the tooth 25 so that the 10 parts assume the position shown in Fig. 4.

In prior devices of this character the ends 27 of the matrix band 24 had to be inserted carefully through one or more aligning slots, each of said slots being closed on all sides, and the 15 threading of the ends of the matrix was a difficult and delicate matter. Furthermore, due to the twisting and the crimping of the ends of the band when the parts assumed the position shown in Fig. 4, it was impossible to disengage the 20 matrix from the band until the nut 13 had been turned in counter-clockwise direction to return the slide bracket 7 into its outer position, as shown in Fig. 2, where the deflected portions of the band are again in alignment with the slots, 25 thus permitting the disengagement of the matrix retainer from the matrix with some difficulty, due to the frictional engagement remaining even after the end of the shaft 21 has been moved away from the outer member 22 of the slide 7 30 to remove all pressure against the ends of the band.

By my present construction it will be seen that it is not necessary to thread the ends of the band through slots closed on all sides, but that, due 35 to the fact that the slots are open across the bottom end of the slotted members 2, as viewed in Fig. 1, the matrix band is disposed about the tooth and the matrix retainer is "dropped" upon the ends of the band which thus automatically 40 enter the slots 3. In operating on the upper jaw the matrix retainer is moved upwardly with respect to the edges of the band which thus enter the slots very easily. Furthermore, by my present construction, after the end 21 of the shaft 45 16 has clamped the ends of the band against the outer member 22 of the slide bracket 7 and after the operating nut 13 has been turned to bring the slide bracket 7 out of alignment with the slots 3, as shown in Fig. 4, it is merely 50 necessary, in order to disengage the parts, to turn the operating nut 19 of the shaft 16 in counter-clockwise direction to draw the end 21 of the shaft away from the outer member 22 of the slide bracket 7, whereupon the matrix retainer 55 can be bodily "lifted" from the matrix regardless of the position of the slide bracket 7 with respect to the slots 3.

In Fig. 6, I have shown a modified form of con-

struction in which, in lieu of providing a slot 3 in each of the members 2, I may provide two or more slots 28 and 29 in each of the members 2, the only requisite being that the slots so provided be open across their bottom ends, as viewed in Fig. 1, in order to permit the application of the retainer to the band by merely "dropping" it on the gathered ends of the band or by "lifting" it from the ends of the band without any difficulty, due to the elimination of frictional engagement and without the necessity of accurately threading the ends of the band in slots which are closed on all sides. 10

I claim:

1. A dental matrix retainer, comprising a supporting bar, juxtaposed fixed members deflected at an angle to one end of said bar and having slots therein adapted to receive the free ends of a matrix band disposed about a tooth being treated, a slide movable longitudinally of said bar and having spaced members deflected at an angle to said bar and to said fixed members, and an operating shaft carried by said supporting bar, a part of said shaft threadedly engaging one of the deflected members of said slide whereby the free end of said shaft may be clamped against the free ends of the matrix band and the other of the deflected members of said slide, and another part of said shaft threadedly engaging a fixed nut at the other end of said bar whereby said slide may be moved longitudinally of said bar towards or away from said fixed members. 30

2. A dental matrix retainer, comprising a supporting bar, juxtaposed fixed members deflected at an angle to one end of said bar and having slots therein adapted to receive the free ends of a matrix band disposed about a tooth being treated, a slide movable longitudinally of said bar and having spaced members deflected at an angle to said bar and to said fixed members, and an operating shaft carried by said supporting bar, a part of said shaft threadedly engaging one of the deflected members of said slide whereby the free end of said shaft may be clamped against the free ends of the matrix band and the other of the deflected members of said slide, and another part of said shaft threadedly engaging a fixed nut at the other end of said bar whereby said slide may be moved longitudinally of said bar towards or away from said fixed members. 35

3. A dental matrix retainer, comprising a supporting bar, juxtaposed members deflected at an angle to one end of said bar and having slots therein adapted to receive the free ends of a matrix band disposed about a tooth being treated, a slide movable longitudinally of said bar and having spaced members deflected at an angle to said bar and to said fixed members, and an operating shaft carried by said supporting bar, a part of said shaft threadedly engaging one of the deflected members of said slide whereby the free end of said shaft may be clamped against the free ends of the matrix band and the other of the deflected members of said slide, and another part of said shaft threadedly engaging a fixed nut at the other end of said bar whereby said slide may be moved longitudinally of said bar towards or away from said fixed members. 40

4. A dental matrix retainer, comprising a supporting bar, juxtaposed members deflected at an angle to one end of said bar and having slots therein adapted to receive the free ends of a matrix band disposed about a tooth being treated, a slide movable longitudinally of said bar and having spaced members deflected at an angle to said bar and to said fixed members, and an operating shaft carried by said supporting bar, a part of said shaft threadedly engaging one of the deflected members of said slide whereby the free end of said shaft may be clamped against the free ends of the matrix band and the other of the deflected members of said slide, and another part of said shaft threadedly engaging a fixed nut at the other end of said bar whereby said slide may be moved longitudinally of said bar towards or away from said fixed members. 45

5. A dental matrix retainer, comprising a supporting bar, juxtaposed members deflected at an angle to one end of said bar and having slots therein adapted to receive the free ends of a matrix band disposed about a tooth being treated, a slide movable longitudinally of said bar and having spaced members deflected at an angle to said bar and to said fixed members, and an operating shaft carried by said supporting bar, a part of said shaft threadedly engaging one of the deflected members of said slide whereby the free end of said shaft may be clamped against the free ends of the matrix band and the other of the deflected members of said slide, and another part of said shaft threadedly engaging a fixed nut at the other end of said bar whereby said slide may be moved longitudinally of said bar towards or away from said fixed members. 50

6. A dental matrix retainer, comprising a supporting bar, juxtaposed members deflected at an angle to one end of said bar and having slots therein adapted to receive the free ends of a matrix band disposed about a tooth being treated, a slide movable longitudinally of said bar and having spaced members deflected at an angle to said bar and to said fixed members, and an operating shaft carried by said supporting bar, a part of said shaft threadedly engaging one of the deflected members of said slide whereby the free end of said shaft may be clamped against the free ends of the matrix band and the other of the deflected members of said slide, and another part of said shaft threadedly engaging a fixed nut at the other end of said bar whereby said slide may be moved longitudinally of said bar towards or away from said fixed members. 55
